APPARATUS FOR GAUGING AND SEPARATING DEFECTIVE LINKS IN AMMUNITION BELTS

Stephen C. Olszewski, Davenport, Iowa

Application May 15, 1946, Serial No. 669,764

24 Claims. (Cl. 209—88)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to a gaging apparatus. More particularly the invention pertains to an apparatus for use in detecting defects in ammunition belts for automatic and semiautomatic weapons.

The successful use and operation of automatic and semiautomatic weapons of the belt-fed type depend to a great extent upon the character of the ammunition and of the belts by means of which such ammunition is fed to the weapon. One of the principal causes for stoppages in a machine gun or similar weapon is failure of the gun to feed. This failure is almost invariably traceable to some defective component of the ammunition belt. Constant effort and research have been devoted by ordnance engineers and designers to the perfection of ammunition belts and feeding mechanisms for weapons of this type and in the main several satisfactory types of ammunition belts have been developed, one of which is of the disintegrating type consisting of a series of similar belt links articulately interconnected by the cartridges. In the use of such a belt in a machine gun, for example, the cartridges are fed into the gun in a path normal to the bore of the gun and the cartridges are successively fired and the cases extracted during a normal cycle interrupted only by the necessity for inserting a new belt.

Experience has shown however that ammunition belts of most any type are subject to the occurrence of several defects in the components thereof, such as, for example, misalignment of cartridges; that is to say, certain of the cartridges may be inserted into the belt so that the nose and base portions thereof project laterally at varying distances from the opposite sides respectively of the series of interconnected belt links. Likewise, the links themselves may be distorted, misaligned or otherwise defective. The same misalignment and distortion will also occur in a belt of the continuous flexible type, that is, in a belt that is not disintegrating but in which a long, flexible weblike element is slitted or otherwise formed to receive cartridges. Although the necessary precautions are taken in the manufacture and assembly of ammunition belts, it has been found that considerable misalignment between the cartridges and belt body and distortion of the belt body or portions or links thereof occurs in the period between the

2

assembly of the belt and the actual use thereof. This is particularly true in instances in which the assembled ammunition belts are transported for great distances and stored for substantial periods under varying circumstances involving rough handling and varying climatic conditions. In such cases, it becomes necessary that using troops recheck the belts before firing.

It is accordingly a principal object of the present invention to provide a simple and efficient apparatus, preferably portable, that may be utilized in forward combat areas by the using troops for the purpose of reconditioning ammunition belts so that defects therein may be eliminated before firing.

It is an important object of the invention to provide an apparatus of this type in which the ammunition belt may be fed through gage means so that defects of misalignment, distortion and the like may be detected, and to include in the apparatus means for extracting and removing cartridges from the portion or component of the belt determined by the gaging means to be defective.

It is another important object of the invention to provide driving means for feeding the cartridges into the gaging means and to incorporate in the driving means control mechanism responsive to the detection of a defective component in the belt for disconnecting the feeding means and for setting into operation means for extracting the necessary cartridge or cartridges.

The invention has for another object the provision of simple control mechanism, preferably electrically operated, which is actuated by the gaging means upon the detection of a defect in the belt and to associate with the control mechanism positive means for continuing operation of the mechanism even though the electrical circuit is interrupted by the absence of a defect in a subsequent portion of the ammunition belt.

Another object of the invention is the provision of means in the driving mechanism constructed and arranged to provide for the operation of such mechanism in predetermined cycles so that the functioning of the feeding means and extracting means are related in a definite cycle of operation, for the purpose of disconnecting the feeding means while the extracting means is operating and to reconnect the feeding means after the extracting operation is completed.

Still other objects of the invention are to provide means for guiding the belt into the gage

means so that the desired relationship between the cartridges and belt or belt links may be properly gaged; to provide gage means including gaging elements that may be easily removed for adjustment or replacement without disturbing other elements of the apparatus; and to provide generally an apparatus of lightweight construction that may be easily and quickly assembled and disassembled and transported from one location to another.

Briefly and specifically the foregoing and other objects are achieved in one preferred form of the invention by the provision of apparatus including a support over which an ammunition belt may be fed through gaging means that operate to detect misalignment between the cartridges and body of the belt. The apparatus further includes means for extracting cartridges from the portion of the belt determined to be misaligned or otherwise defective. In the use of the apparatus with an ammunition belt of the disintegrating type the extracting means is arranged to extract a pair of adjacent cartridges so that the defective link may be removed from the belt series. Upon the detection of a defect in a belt link or other portion of the belt, the gage means operates to close an electrical circuit to a first solenoid which in turn closes a second circuit to a second solenoid for the purpose of controlling the drive means so that operation of the belt-feeding means is interrupted and operation of the cartridge-extracting means is established. A secondary actuating means is provided in conjunction with the first solenoid so that the second circuit remains closed even though the first circuit is broken because of the absence of a defect in a subsequent or portion of the belt link and so that the time lag between the detection of a defective link and the beginning of the cycle of extraction does not preclude the stopping of the feeding mechanism. The extracting mechanism is so arranged that the cartridges are extracted or withdrawn and caused to retain positions corresponding to their original positions in the belt so that the cartridges may be ejected or deposited in such a manner that they may be easily collected and used again, if not defective, in the same belt or in other ammunition belts of the same type.

A complete understanding of the construction and operation of the invention and the various features thereof may be had from the following detailed description of a preferred embodiment of the invention as illustrated in the accompanying sheets of drawings in which:

Fig. 1 is a plan view of the apparatus;

Fig. 2 is a side elevational view of the apparatus shown in Fig. 1, the illustration being on a somewhat enlarged scale and being partly in section as viewed along the line 2-2 of Fig. 1;

Fig. 3 is an end elevation of the apparatus shown in Figs. 1 and 2;

Fig. 4 is a transverse sectional view taken substantially on the line 4-4 of Fig. 1;

Fig. 5 is a horizontal sectional view, on an enlarged scale, of the driving means for the feeding mechanism and extracting mechanism, the view being taken substantially along the line 5-5 of Fig. 2;

Fig. 6 is a fragmentary view on an enlarged scale showing the driving head and feed pawl of the feeding mechanism;

Fig. 7 is an enlarged detailed view showing the timing or clutch wheel;

Fig. 8 is an enlarged transverse sectional view illustrating a preferred form of belt-gaging means,

the view being taken substantially on the line 8-8 of Fig. 4;

Fig. 9 is a diagrammatic illustration of the electrical circuits involved in the control mechanism and the association thereof with the various control components; the latter being likewise illustrated diagrammatically, both as to structure and relative location;

Fig. 10 is a longitudinal sectional view taken substantially on the line 10-10 of Fig. 4 and showing the spring mounting of the cartridge nose guide;

Fig. 11 is a longitudinal sectional view taken substantially on the line 11-11 of Fig. 4 and showing the construction of the lower extractor jaw; and

Fig. 12 is an end elevational view of the timing, rockshaft and yoke structure, with the gear casting illustrated in phantom.

Figures 13 and 14 are respectively an elevational and a plan view, illustrating in detail the connection for operating the control arm.

The supporting structure is preferably built up of a plurality of castings, rigidly connected together and provided with suitable supports, and a trough or channel on which the belt may be supported and fed through the gaging means. As best shown in Figs. 1, 2 and 3, the supporting structure includes a first casting 20 having a rear flange 21, (right hand as viewed in Figs. 1 and 2) formed generally as a U having opposite, vertical leg portions 21a and 21b, against which is abutted the forward portion of a longitudinally extending channel or trough 22. As shown in Fig. 3, the cross section of the channel 22 is coincident with the inner edges of the U-shaped flange 21 and both are shaped to conform to the cartridges of an ammunition belt to be carried thereby and to pass there through. A vertical leg 23 is rigidly but removably secured to this structure at the junction of the flange portion 21a and channel 22. A similar leg 24 is provided at the other side of the casting and trough and is secured to the flange portion 21b. The trough or channel 22 is extended a suitable distance rearwardly and is supported at its rear end by a pair of legs (not shown) similar to the legs 23 and 24. The length or extent of the trough 22 depends upon the length of the ammunition belt to be supported and this of course may vary according to circumstances.

The casting or housing 20 is provided with a front flange 25, also formed generally as a U having opposite, vertical flanged legs 25a and 25b (Fig. 1), that parallels and is aligned with the rear flange 21 and that serves as means for mounting a second hollow casting structure 26, the interior construction of which will be described below. This casting 26 has an apertured, transverse rear flange 27, rigidly but removably secured to the flange 25 of the casting 20 (Fig. 1), and a parallel front edge portion 28 against which is abutted the rear face of a trough or channel 29 similar to the trough 22. The rear end of the trough 29 and each of the opposite sides of the edge portion 28 form junctions which respectively receive the upper ends of a pair of supporting legs 30, preferably of the type previously described. The front edge portion 28, trough 29 and legs 30 are rigidly but removably secured together. The relationship between the two troughs 22 and 29, the two castings 20 and 26 and the legs 23, 24 and 30 is such as to provide, when assembled, a rigid unitary structure. It will be noted that these parts may be easily and quickly disassembled for repair or replacement or for easy transport thereof.

The housing 26 is provided at one side thereof with a vertical flange 31 that parallels the main axis of the trough 22 (Fig. 1). This flange is secured to a complementary flange 32 formed on a third casting 33. The casting 33 has its main body portion extending at right angles to the previously described structure and has its free end provided with a transverse supporting member 34 carried at its opposite sides by the upper ends of a pair of legs 35 similar to the legs 23, 24 and 30 previously described (Fig. 1). The side of the casting 26 opposite the flange 31 is provided with an integral longitudinal supporting portion 36 provided with upper and lower horizontally extending flanges 37 between which is supported and rigidly secured, as by bolts 38, a casting or bracket 39. This bracket is preferably in the form of a casting having opposite vertical flanges 40 to which are rigidly secured the upper ends of a pair of supporting legs 41. The front (left hand side, Fig. 1) of the vertical flange 32 on the casting 33 includes a secondary flange 42 that is in transverse alignment with the front edge 28 of the casting 26 and that is secured to the proximate supporting leg 30; a similar flange 43, transversely aligned with the secondary flange 42, is formed on the front end of the longitudinal supporting portion 36 and is secured to the other leg 30. The other or rear side of said vertical flange 32 has formed thereon a secondary flange 44 (Figs. 1 and 2), which is secured to the front flange leg 25a of the casting 20. The rear end of the longitudinal supporting portion 36 is formed with a flange 43a (Fig. 1), which is located at the side of the flange 27 opposite and in transverse alignment with the secondary flange 44 at the rear of the flange 32 on the casting 33. This flange 43a is secured to the other flange leg 25b of the casting 20. The relationship between the castings 26, 33 and 39 and the legs 35 and 41 is such that the parts may be easily and quickly disassembled, and this structure, in conjunction with the casting 26 and legs 23 and 30, forms a unitary organization when assembled.

As best shown in Fig. 3, the housing 20 is provided with a belt supporting tray or trough portion 45 generally shaped to conform to a cartridge lying on its side. It will be noted also from this figure that the bottom of the trough or channel 22 is coincident with the bottom of the tray portion 45. The ammunition belt, when supported on the trough 22, is thus properly fed and guided over the tray 45 and to the gage means to be presently described.

The housing 26 is preferably formed of separable upper and lower halves 46 and 47 (Fig. 4) and the interior of the composite casting 26 formed thereby includes at one side thereof horizontally disposed guide portions 48 spaced vertically apart and shaped to receive the base ends of cartridge cases of cartridges in the belt. Similarly spaced apart portions 49 are provided at the opposite sides of the casting halves 46 and 47 and serve as an opening through which the nose portions of the cartridges pass as the belt is fed through the casting 26. The upper surfaces of the lower portions 48 and 49 are in effect extensions of the bottom of the tray 45. The longitudinal vertical portion at one side of the tray 45 in the casting 20 provides a longitudinal guide 50 against which the rims of the cartridges may seat, (Figs. 1 and 3). This guide cooperates with the trough 22 (left-hand side as viewed in Fig. 3), the lower portion of the tray 45, and with the 75

guide portions 48 and 49 to guide the ammunition belt in its travel through the apparatus.

As best shown in Fig. 4, the supporting portion 36 of the casting 26 has slidably mounted between the vertically spaced apart horizontal flanges 37 thereof a longitudinally extending guide 51 (Fig. 10) having its inner face cut out to provide a longitudinal groove 52 in which the nose portions of the cartridges may seat. The member 51 is formed with two pairs of integral upper and lower ears 53 each of which receives a vertical pin 54 which serves to connect the member 51 to a pair of rods 55 mounted in bores in the bracket 39. As best shown in Fig. 10, each rod 55 is provided at its free end outside of the bracket 39 with stop means 56 in the form of a nut and washer. The bores in the bracket 39 are enlarged and each houses a compression spring 57 the function of which is to urge the guide member 51 into engagement with the nose portions of the cartridges. This arrangement provides spring-pressed means serving to seat the rear portions of the cartridges firmly against an extension of the guide 50, as will hereinafter appear.

As best shown in Fig. 1, the casting 33 is of elongated structure having opposite, parallel side rails 60 delineating an elongated opening 61. The side rails 60 serve to support slidably thereon a reciprocable extracting element 62. This element is provided with a guide 63 (Fig. 11) that extends parallel to the path of travel of the ammunition belt and that is further aligned with and in effect forms an extension of the longitudinal guide wall 50 in the casting 20, (Fig. 4). The guide 63, like the guide wall 50, serves as means against which the rims of the cartridges may seat. The spring-pressed member 51 serves to seat the cartridges firmly and accurately against the guide 63.

The extracting element 62 has pivoted thereon upper and lower jaws 64 and 65, each of which has its forward portion formed to engage the extracting groove of a cartridge. In the present instance the jaws 64 and 65 are of sufficient transverse extent to provide for the gripping of a pair of adjacent cartridges (Fig. 11). The jaws are respectively pivoted on pins 66 and 67 each of which carries a torsion spring 68 providing resilient means for urging the jaws into gripping relation with the extracting grooves of a pair of adjacent cartridges. The extracting element 62 has formed thereon at its under side a pair of depending ears 69 which carry a transverse pin 70 for pivotally connecting to the ears a pair of reciprocating links 71 by means of which the extracting element 62 may be reciprocated on the slide rails 60 of the casting 33. The driving means for reciprocating the links 71 will be described below in connection with the description of the driving mechanism for feeding the ammunition belt.

The rear portion of the casting 33 includes a stop member 72 against which the rear portions 65 of the jaws 64 and 65 may abut. This action effects separation of the gripping portions of the jaws and permits the cartridges to be dropped downwardly through the opening 61 in the casting 33. The gripping portion of the lower jaw 65 is provided with a forward extension 73 that is adapted to project along and under the base portion of the cartridges. This extension serves to support the cartridges during the extracting operation so that the cartridges are held in a horizontal position corresponding to the former

positions thereof in the belt so that, upon release of the jaws by the stop 72, the cartridges may drop in a generally horizontal position through the opening 61 and be so deposited as to be easily and quickly collected and used again. The upper jaw 64 has a pair of transversely spaced, rearwardly directed tail portions 74, and the lower jaw 65 has but a single tail portion 75 (Figs. 2, 4 and 11). When the jaws 64 and 65 are separated upon abutting the stop 72, the tail 75 on the jaw 65 may move between the two tail portions 74 on the jaw 64, thus providing for maximum separation of the jaws.

The housing 20 is provided with a pair of upstanding bracket portions 79 carrying at their upper ends a transverse rockshaft 80 on which is keyed a depending arm 81. The lower portions of the brackets 79 at their junctions with the main body portion of the casting 20, are respectively provided with integral longitudinal keys 82 (Fig. 3), which serve to carry for reciprocation thereon a driving head 83 having at its opposite sides keyways slidably engaging the keys 82. The lower portion of the depending arm 81 is formed with a transverse, vertically elongated opening 84 in which is carried a transverse pivot pin 85 (Fig. 6) to which is pivotally connected a lug 86 adjustably secured to the driving head 83 by means of a slot 87 in the lug (Figs. 1 and 6) and a bolt 88 passed therethrough and through the driving head 83. The driving head further includes an integral, transverse vertical flange 89 which has a threaded bore into which is threaded a shank 90 that is preferably formed integral with and extends forwardly from the lug 86. Lock nuts 91 are threaded on the shank 90 at opposite sides of the flange 89 and serve, in conjunction with the slot 87 and bolt 88, as means by which the driving head 83 and lug 86 may be adjusted along the line of reciprocation of the parts. The driving head further includes, preferably integrally therewith, a pair of forwardly extending ears 92 which carry a transverse pivot pin 93 on which is pivotally mounted a feeding pawl 94, (Fig. 6). The lower portion of the pawl is adapted to engage links in the belt as the driving head is reciprocated to feed the ammunition belt. The upper portion of the pawl is engaged by a spring-pressed plunger 95 carried between the flange 89 and a drilled parallel flange 96 formed on the driving head 83 adjacent the pawl 94. The transverse rockshaft 80 at the upper ends of the brackets 79 on the casting 20 is extended at one end and has keyed thereto the upper end of a driving arm 97. This arm is reciprocated by driving mechanism the details of which will be set forth in connection with the description of the driving of the extracting mechanism.

Fig. 8 illustrates a portion of an ammunition belt of the disintegrating type in which a series of like belt links 100, preferably formed of metal or other suitable material, are articulately interconnected by cartridges. Each link includes a pair of spaced, coaxial, cartridge-gripping loops 101 and an integral, single connecting loop, 102 formed about an axis paralleling the axis of the loops 101 and extending from the link body in substantial alignment with the space between the loops 101 so that it interfits with the space between the loops 101 of an adjacent link (Figs. 1, 3 and 4). A cartridge passes through the spaced loops 101 of one link and through the single loop 102 of an adjacent link and serves as a pivot

or pintle for articulately connecting adjacent links.

As previously mentioned, it is vital in the assembly of the completed belt that the cartridges and links be properly aligned with the respect to the main axis of the body of the belt. In other words, all the cartridges must be inserted in the links so that the base portions of the cartridges project the same distance at one side of the series of links 100. It is also important that the nose portions of the cartridges project uniformly from the opposite side of the belt links. Still further, it is important that the transverse dimension between opposite sides of the spaced loops 102 of each belt link 100 be maintained within rather close tolerances. For the purpose of the present disclosure, this latter dimension is indicated at "A" in Fig. 1. The distance "B" in Fig. 1 represents the distance between a line containing the front sides or edges of the front loops 102 of the series of links and the line on which the rims or bases of all cartridges should lie. It is an important function of the apparatus constructed according to the present invention to check or gage ammunition belts for the purpose of determining that the dimensions A and B, among others, are within the limits of the prescribed tolerances and to remove from the belt any link or links that do not meet the specifications.

30. It will be readily seen that these dimensions are subject to variance because of the conditions incident to the handling and storage of the ammunition belts. For example, excessively rough handling of the containers in which the belts are shipped or transported is likely to result in axial displacement of certain of the cartridges with respect to the links. Also, climatic conditions may result in contraction or expansion of the links, either of which conditions normally causes distortion of the links, particularly because of the fact that the links are composed of metal or other material that differs from the metal of the cartridge case. Experience has shown that relatively slight misalignment of cartridges or distortion of links may result in serious stoppages in weapons in which the belt is being used. It is proposed by the present invention to provide apparatus by means of which the belt links may be rechecked a short time before firing so that there is eliminated or reduced to a minimum the possibility that stoppage may occur as a result of failure of the weapon to feed because of a defective cartridge belt.

For the purpose of checking the dimensions 55 A and B as previously described, the apparatus herein set forth is provided with gage means between which the ammunition belt is fed. As set forth above, the casting 26 is preferably formed of upper and lower halves 46 and 47. As best shown in Fig. 4, the upper half is provided at its top with an opening 110 closed by a removable cover 111. The casting half 47 is provided at its bottom with a similar opening 112 closed by a removable cover 113. Each cover 60 element 111 and 113 is rigidly attached to parts 46 and 47 respectively, of casting 26, by means of bolts, not shown, and serves to mount a gaging element 114, there being an upper and a lower element for the purpose of checking both upper and lower portions of the ammunition belt links.

As shown in Figs. 4 and 8, each gage element 114 comprises a main body portion having a pair of gage members 115 spaced apart in a direction axially of the cartridge. Each gage element 114 75 is supported from its respective supporting cover

111 or 113 by means of a pair of spaced, flat steel springs 116. The spacing between the inner portions of the gage members 115 on the gaging elements 114 is set at the dimension A (Fig. 1) and the gage members are so positioned as to be enabled to detect any lateral or transverse distortion or displacement of the links 100. The front gage member of each element 114 is spaced from the guide 50 a distance equal to the distance B (Fig. 1). The spring mounting of the gaging elements permits shifting thereof in accordance with the detection of distortion, displacement or other defects in the links.

Shifting of either gaging element in response to the detection of defects in the ammunition belt is utilized to effect the operation of actuating and control mechanism for discontinuing the operation of the feeding mechanism and for initiating operation of the extracting mechanism. According to the preferred embodiment of the present invention herein described, the actuating and control mechanism combines the use of electrical circuits and mechanical means in such a manner that the control of the feeding and extracting mechanisms is simple and positive.

Each of the portions 49 in the casting 26 carries a transverse pivot pin 120 on which is pivotally mounted a control or switch arm 121 (Fig. 4). The portion of the arm within the casting 26 is provided with a pair of control pins 122 spaced apart on an extended diameter of the pivot pin 120. Each gaging element 114 carries an operating finger 123 that is preferably formed as a T having the crossbar thereof engageable with the control pins 122 on the control arm 121. The arrangement is such that shifting of the gaging element in either direction will serve to rock the control arm 121 in a counterclockwise direction. A compression spring 124 is engaged between each control arm 121 and a proximate portion of the supporting portion 36 of the flanges 37. The force available from the spring 124 is sufficient only to maintain the control arm 121 in its neutral position and is not sufficient to cause misalignment or displacement of either gaging element in either direction. The bracket 39 carries upper and lower supporting members 125 each of which in turn carries an electrical switch 126. Each switch includes an operating plunger 127 normally engageable with an adjustable stud 128 on the control arm 121. The arrangement is such that rocking of either of the control arms 121 in response to shifting of either gage element 114 will effect closing of electrical contacts in the respective switch 126. Fig. 9 is a diagrammatic illustration of the electrical circuit which includes the switches 126 and other components to be presently described.

As best shown in Fig. 4, the upper portion of the casting 26 carries therein a rockshaft 130 disposed on an axis transverse to the axes of the cartridges in the ammunition belt. This rockshaft has keyed thereto an upwardly extending switch arm 131 normally spring-pressed in a clockwise direction by a spring and plunger assembly 132 connected between the arm and a bracket 133 mounted on the upper cover 111 of the casting 26. The upper portion of the casting 33 adjacent its connection with the casting 26 is formed with a transverse bracket 134, which is spaced above the extracting slides 50 and which carries electrically-energizable device such as a solenoid 135. The plunger of this solenoid is extendable to engage the switch arm 131. The upper cover 111 of the casting 26 is further pro-

vided with a bracket 136 (Fig. 1) which supports an electrical switch 137 having its plunger 138 in position to be engaged by the switch arm 131 as that arm is rocked in a counterclockwise direction by action of the solenoid 135. The solenoid 135 is connected to both switches 126 so that actuation of either switch serves to energize the solenoid and consequently, through the solenoid plunger and arm 131, to actuate the switch 137 and to close the circuit therethrough (Fig. 9).

The rockshaft 130 on which the swinging arm 131 is mounted, has keyed thereto a lever 140 which extends rearwardly above and parallel to the extractor element 62 (Figs. 2 and 4). The free end of the lever is provided with a pair of depending ears 141 which carry a transverse pin 142 on which is mounted a pair of spaced, aligned pawls or catches 143, each of which is tensioned by a torsion spring 144 for pivoting in a counterclockwise direction. An upper portion of the extracting element 62 is provided with an integral transverse bar or lug 145 and, in the normal position of the lever 140 and pawls 143, a lower arm 146 on each pawl engages the front edge of the lug or bar 145 on the extractor element. Stated otherwise, the pawls are cocked by the lug 145 when the extractor 62 is in its initial position. When either of the switches 126 is actuated to energize the solenoid 135 for rocking of the rockshaft 130 and swinging of the switch arm 131, the lever 140 is swung upwardly and the arms 146 of the pawls 143 are released from the front edge of the lug 145 on the extractor element 62. The lever 140 is provided with stop lugs 147 which limit movement of the pawls 143 to positions in which the arms 146 engage the upper surface of the lug 145 and extend vertically between the lug and the lever 140, thus maintaining the actuated position of the switch arm 131. As will be hereinafter more clearly brought out, the pawls 143 are cocked and the lever 140 restored to its original position after completion of the extraction cycle.

The switch 137 is electrically connected to control means for controlling the operation of the driving mechanism for the feeding means and the extracting means. As best shown in Figs. 2 and 3, the lower portion of the casting 20 is provided with a horizontal flange 150 which serves as means for mounting a gear casing or housing 151, the casing being provided with a complementary flange 152 rigidly but removably secured to the flange 150 on the casting 20. The gear casing is preferably formed of upper and lower halves removably secured together and forming axially aligned bearings 153 and 154 for the journaling of a driving shaft 155 (Fig. 5). This shaft extends beyond the bearing 154 and is connected by a suitable coupling 156 to any suitable source of power, herein indicated as an electric motor 157.

As shown in Fig. 5, the shaft 155 is provided intermediate its ends with a splined portion 158 which carries thereon an axially shiftable clutch member 159 operable by means of a shifter yoke 160 of conventional construction. The shifter yoke is keyed to a rockshaft 161 journaled in an upper portion of the casing 151 on an axis at right angles to the axis of rotation of the driving shaft 155 (Fig. 12). The exterior of the housing 151 has secured thereto a bracket 162 (Fig. 2) on which is mounted a second electrically-energizable device such as a solenoid 163. This solenoid is connected in an electrical circuit closed by actuation of the switch means 137 and

includes a plunger engageable with an arm or lever 164 keyed to the outer end of the rockshaft 161. It will be seen that actuation of the solenoid by closing of the switch means 137 results in rocking of the rockshaft 161 and thus shifts the clutch member 159 on the spline 158 of the driving shaft 155. The shaft 155 has journaled thereon at one side of the clutch member 159 a first driven member 165 which is provided with clutch teeth engageable with the clutch teeth at the proximate end of the clutch member 159. The driven member 165 has preferably formed integrally therewith an axially extending sleeve to which is keyed a bevel pinion 166 which meshes with a bevel pinion 167 keyed to one end of a short shaft 168 disposed on an axis at right angles to the axis of the shaft 155 and journaled at one end in a bearing 169 in a wall of the casing 151 and at its other end in a bearing 170 formed at an interior portion of the casing 151. The shaft 168 has keyed thereto intermediate the bearings 169 and 170 a pinion 171 which is in constant mesh with a gear 172 keyed to a crankshaft 173 which parallels the short shaft 168 and is journaled in the side wall of the housing 151 that carries the bearing 169. The crankshaft 173 has keyed thereto outside the housing 151 a crank 174. A longitudinally slotted connecting arm 175 has its upper end bifurcated to provide a pair of split ears 176 which are connected by pivot pins 177 to the forward ends of the reciprocating links 71 for the extractor element 62 (Fig. 4). A depending bracket 178 is rigidly carried at its upper end by the gear casing 151 and is provided at its lower end with a pivot 179 that mounts the lower end of the connecting arm 175. The crank pin of the crank 174 carries a slide block 174a which connects the crank 174 to the arm 175 by means of the slot in the latter, thus providing for transforming the rotational motion of the crank arm 174 into oscillatory motion of the arm 175.

As further shown in Fig. 5, the clutch member 159 is normally positioned out of driving engagement with the driven member 165 and is in driving engagement with a second driven member 180 which is journaled in the bearing 153 and which serves to journal the end of the shaft 155. It will be understood of course that the proximate ends of the clutch member 159 and second driven member 180 are provided with complementary engageable teeth. The outer end of the driven member 180 is formed as a sleeve which extends outside the housing 151 and which has keyed thereto a crank 181 to a crankpin 182 of which is connected the lower end of the oscillating arm 97, which, as previously described, effects reciprocation of the driving head 84 of the feeding means for the ammunition belt.

As previously stated, it is an important object of the present invention to provide means associated with the driving means for timing the driving of the feeding mechanism and extracting mechanism so that the feeding and extracting functions will be alternately performed; that is to say, so that the extracting mechanism is inoperable while the feeding mechanism is operating and so that the extracting mechanism is set into operation when the drive to the feeding mechanism is interrupted. For this purpose the crankshaft 173 has keyed thereto, at its end within the housing 151 and adjacent the gear 172, a circular rotatable member 185 which, as best shown in Fig. 7, has its circular periphery interrupted by a notch 186. The rockshaft 161 has keyed thereto within the housing 151 a de-

pendent rocker arm 187 which has at its other end a pair of spaced lugs 188 normally engageable with the notch 186 (Fig. 12). The lugs 188 carry a stub shaft 189 on which is pivotally mounted a roller 190. A tension spring 191 is connected between the intermediate portion of the arm 187 and an eyebolt 192 carried by an intermediate wall portion of the gear casing 151. The spring 191 is comparatively powerful and exerts a force tending to maintain engagement between the lugs 188 and the arm 187 and the notch 186 in the rotatable element or wheel 185. It will be noted that the rocker arm 187 and the solenoid-actuated arm 164 are on the same rockshaft 161 (Fig. 12) and that upward swinging of the arm 164 results in swinging of the arm 187 in a counterclockwise direction so that the lugs 188 are disengaged from the notch 186; the wheel 185 is thus rotated, since the rocking of the shaft 161 simultaneously results in shifting the clutch member 159 out of engagement with the feed-mechanism driven member 180 and into driving engagement with the extractor-mechanism driven member 165. The roller 190 rides on the periphery of the wheel 185 until the wheel completes one revolution, after which the spring 191 returns the arm to its original position so that the lugs 188 again engage in the notch 186.

In the operation of the preferred form of the invention herein illustrated and described, an ammunition belt, preferably consisting of the links 186 articulately interconnected by the cartridges, is placed in the channel or trough 22 and the leading portion of the belt is fed into the opening 45 in the first casting 20. The bases or rims of the cartridges will be properly seated against the longitudinal guiding wall 50 because of the shape of the trough 22. The feeding pawl 94 is engaged with the leading belt link and the driving motor started to drive the shaft 155, which through the spline 158, clutch member 159 and feed-mechanism driven member 180 rotates the crank 181, thereby effecting oscillation of the arm 97 and reciprocation of the feed-mechanism driving head 83 to feed the belt through the opening 45 and subsequently through the gaging elements 114. As the belt is fed through the gaging means the dimensions "A" and "B" (Fig. 1) will be checked by the gaging portions 115. In the event that distortion of a link has affected dimension "A" or displacement or misalignment has affected dimension "B," the presence of either of these defects will be immediately detected or determined by the gage portions 115. It is immaterial whether the defect in the belt be in an upper or lower portion or at either side thereof, since, as previously pointed out, the arrangement of the gage means is such as to check any of these portions of the belt, and the mounting of the gaging elements on the spring members 116 is such that movement thereof in either direction will effect actuation of the respective switch 129 to close the circuit to the first solenoid 135. The switches 126 are preferably of the type known as "Micro switches" which, as is well known to those skilled in the art are relatively sensitive. Therefore, slight movement of either gage element in response to a defect in a belt link will result in completion of the circuit to the solenoid 135. Energizing of the solenoid 135 effects extension of the solenoid plunger and consequent swinging of the switch arm 131 into engagement with the contact plunger 138 of the switch 137, thus completing the circuit to the second solenoid 163. Initial rocking of the shaft 130, on which the

arm 131 and lever 140 are mounted, serves to release the lower arms 146 of the cocked pawls 143 from the bar or lug 145 on the extractor 62 so that the pawl arms 146 swing about under tension of the springs 144 and engage the upper surface of the lug or bar 145 on the extractor element 62. This action results in maintaining the switch arm 131 in position closing the switch 137, and the circuit to the solenoid 163 remains closed even though the circuit to the solenoid 135 is broken since the switch arm is held by the lever 140 and pawls 143. The circumstance in which this circuit could be otherwise broken would possibly occur if the particular defect in the link were comparatively slight so that the feeding mechanism, in the time lag between detection of the defect and interruption of the drive to said feeding mechanism might tend to continue feeding the belt, with the result that the defective portion of the link might be moved past the gaging means and slightly out of reach of the gaging portions 115. In that event, the feeding mechanism would continue to feed the belt and extraction of the necessary cartridges would not occur and, consequently, the defective link would not be removed. However, since the released pawls 143 swing the lever 140 upwardly and maintain the switch arm 131 in contact with the plunger 138 of the switch 137, completion of the circuit to the solenoid 163 is assured. In this manner, positive control means is provided for disconnecting operation of the feeding mechanism and for establishing operation of the extracting mechanism.

Energizing of the solenoid 163 causes extension of the plunger thereof into engagement with the arm 164 on the rockshaft 161 in the housing or gear casing 151. Rocking of the shaft 161 in a counterclockwise direction serves, by means of the yoke 160, to shift the clutch member 159 out of engagement with the feed-mechanism driven member 180 and into engagement with the extracting-mechanism driven member 165. At the same time, the rocker arm 187 is swung so that the lugs 188 thereon are disengaged from the notch 186 in the wheel 185. Engagement of the clutch member 159 with the extracting mechanism driven member 165 drives the gear 172 and wheel 185 by means of the bevel pinions 166 and 167, shaft 170 and pinion 171, thus rotating the crankshaft 173 and crank arm 174. Rotation of the crank 174 effects oscillation of the extracting-mechanism swinging arm 175, which, by means of the links 71 and pins 70 and 177 moves the extracting element 62 rearwardly and then forwardly on the extractor slides 61 on the casting 33. In the normal position of the extractor jaws 64 and 65, the gripping portions thereof will be associated with the guiding portion of the guide 63 so that the cartridges may pass therethrough; that is, the gripping portions of the jaws 64 and 65 provide projections through which the extracting grooves of the cartridges will pass in the absence of the detection of any defects in the ammunition belt (Fig. 4). Upon actuation of the solenoid 163 to discontinue operation of the feeding mechanism and to establish operation of the extracting mechanism, rearward movement of the extracting element 62 effects extraction of a pair of adjacent cartridges. An examination of the belt shown in Fig. 1 will indicate that the extraction of two adjacent cartridges is necessary to free a link from the belt assembly.

During rearward travel of the extracting element 62 in the first half of the extraction cycle, the extracted cartridges are supported substan-

tially horizontally, this result being achieved by the projecting supporting portion 73 at the forward end of the lower jaw 65 (Fig. 4). At the end of the rearward stroke of the extractor element 62, the rearward portions of the jaws 64 and 65 strike the stop 72 and the jaws are spread apart and the cartridges are allowed to drop downwardly through the lower opening 61 in the casting 33. The ejection of the cartridges is such

that the cartridges are substantially horizontal as they drop downwardly below the apparatus. In the event that the cartridges are permitted to drop directly to the ground or floor beneath the apparatus, the disposition thereof will be orderly and such as will facilitate collection thereof for subsequent use. If it is desired, a collecting means or conveyor or other suitable device may be associated with the apparatus for the purpose of gathering or carrying away the ejected cartridges.

As the extractor element 62 moves rearwardly, the lug 145 thereon is moved out from under the arms 146 on the pawls 143 on the lever 140 and the lever 140 is permitted to return to its initial position, return movement thereof being effected by action of the spring 132 against the switch arm 131. In the event that the circuit to the solenoid 135 has been broken, return action of the switch arm 131 is unopposed. On the other hand, if the solenoid 135 is still energized because either of the switches 126 is closed, the switch arm 131 will not return to its initial position. However, failure of the switch arm to return is immaterial, since it can have no effect on the operation of the driving mechanism in the gear casing 151, for the reason that the clutch member 159 has already been shifted into engagement with the extracting-mechanism driven member 165 which, as aforesaid, causes rotation of the wheel 185. As previously set forth, the lugs 188 and roller 190 on the rocker arm 187 are disengaged from the notch 186 in the wheel 185 and, during rotation of the wheel 185, the roller 190 rides on the periphery thereof. Consequently, even though the circuit to the solenoid 163 is broken, the relationship between the arm 187 and the wheel 185 prevents reverse rocking of the rockshaft 161, and shifting of the clutch member 159 out of engagement with the extracting-mechanism driven member 165 is prevented until the wheel 185 has made one complete rotation. As the wheel 185 rotates, the extraction cycle is being performed; this cycle will be completed simultaneously with the completion of one revolution by the wheel 185 and the spring 191, in continuous tension against the arm 187, will return the arm to its initial position so that the lugs 188 again engage the notch 186 in the wheel 185. At the same time return action of the arm 187 will rock the rockshaft 161 in a clockwise direction so that the yoke 160 shifts the clutch member 159 out of engagement with the extracting-mechanism driven member 165 and back into engagement with the feed-mechanism driven member 180. The normal starting phase of the apparatus includes engagement of the clutch member with the feed-mechanism driven member 180, since, unless the solenoid 163 is energized, the spring 191 will maintain the arm 187 in that position in which the lugs 188 on the arm engage the notch 186 in the wheel 185.

It will be seen from the foregoing description that the above enumerated and other objects of the invention are completely achieved by the preferred form of the invention herein illustrated.

The apparatus lends itself to the adaptations of using troops so that ammunition belts may be quickly and accurately checked before actual firing thereof. The apparatus is constructed of a minimum number of components or units that are easily and readily assembled and disassembled so that the apparatus may be quickly transported from one location to another. This construction likewise lends itself to facilitating of repairs and adjustments. Furthermore, the gaging elements 114, being carried by the removable covers 111 and 113, are easily disassembled from the apparatus for adjustment, repair or replacement. The combination of the electrical circuits and the mechanical means such as the cocked pawl 141 and one-revolution timer wheel 125 is such that adequate control is had over the functioning of the feeding and extracting mechanisms.

Other features of the invention will undoubtedly occur to those skilled in the art. Likewise, the foregoing description and illustration will suggest several modifications and alterations in the preferred form of the invention set forth, all of which may be made without departing from the spirit and scope of the invention as set forth in the appended claims.

What is claimed is:

1. Apparatus for the detection of defective components in an ammunition belt of the type consisting of a series of like belt links articulately interconnected by cartridges, comprising belt-feeding mechanism including supporting means for such belt, gaging means arranged to detect a defective component in the belt, mechanism for extracting a pair of cartridges from the component determined to be defective, driving mechanism for said feeding mechanism and for said extracting mechanism and including a driving element, a first driven element arranged to drive said feeding mechanism, a second driven element arranged to drive said extracting mechanism, clutch means shiftable between said driven elements and selectively positionable to connect either driven element to said driving element, a rockable control member, means on said control member connected to said clutch means for shifting said clutch means upon rocking of said control member, means operably connected between said control member and said gaging means and operable in response to detection of a defective component by said gaging means to rock said control member for shifting said clutch means from said first driven element to said second driven element, and timing means connected to said control member and operable in response to predetermined operation of said extracting mechanism to rock said control member for re-shifting said clutch means from said second driven element to said first driven element.

2. Apparatus for the detection of defective component in an ammunition belt of the type consisting of a series of like belt links articulately interconnected by cartridges, comprising belt-feeding mechanism including supporting means for such belt, gaging means arranged to detect a defective component in the belt, mechanism for extracting a pair of cartridges from the component determined to be defective, driving mechanism for said feeding mechanism and for said extracting mechanism and including connectible and disconnectible drive means for each mechanism, control means arranging said drive means so that normally said feeding mechanism is connected for driving and the drive to said extracting

mechanism is disconnected, means connecting said control means and said gaging means and operable in response to the detection of a defective belt component for simultaneously disconnecting said feeding mechanism drive means and connecting said extracting mechanism drive means, and means connected to said control means and operable in response to completion of extraction by said extracting means to actuate said control means for disconnecting said extracting mechanism drive means and connecting said feeding mechanism drive means.

3. Apparatus for the detection of defective components in an ammunition belt of the type consisting of a series of like belt links articulately interconnected by cartridges, comprising belt-feeding mechanism including supporting means for such belt, gaging means arranged to detect a defective component in the belt, mechanism for extracting a pair of cartridges from the component determined to be defective, driving mechanism for said feeding mechanism and for said extracting mechanism and including a driving element, a first driven element arranged to drive said feeding mechanism, a second driven element arranged to drive said extracting mechanism, a connecting element selectively connectible and disconnectible between the driving element and either of said driven elements and normally connected to said first driven element, means connected between said connecting element and said gaging means and operable in response to detection by said gaging means of a defective component to disconnect said connecting element from said first driven element and to connect said connecting element to said second driven element, and means connected between said control means and said second driven element and operable in response to predetermined movement of the latter to disconnect said connecting element from said second driven element and to connect said connecting element to said first driven element.

4. Apparatus for the detection of defective components in an ammunition belt of the type consisting of a series of like belt links articulately interconnected by cartridges, comprising a support for such belt, means for feeding the belt across said support, gage means associated with said support and arranged to detect defective components of the belt, disconnectible means for driving said feeding means, means operably connected between said gage means and said drive means for said feeding means and responsive to the detection of a defective component in the belt to disconnect said drive means, means for extracting a pair of cartridges from a component determined by said gage means to be defective, connectible drive means for said extracting means, and means responsive to the detection of a defective link by said gage means to connect said drive means for the extracting means.

5. Apparatus for the detection of defective components in an ammunition belt of the type consisting of a series of like belt links articulately interconnected by cartridges, comprising a support for such belt, means for feeding the belt across said support, gage means associated with said support and arranged to detect defects in components of the belt, disconnectible means for driving said feeding means, means operably connected between said gage means and said drive means for said feeding means and responsive to the detection of a defective component in the belt to disconnect said drive means, means

for extracting a pair of cartridges from a component determined by said gage means to be defective, connectible drive means for said extracting means, and means responsive to disconnection of said drive means for said feeding means to connect said drive means for the extracting means.

6. Apparatus for the detection of defects in an ammunition belt of the flexible type containing a series of removable cartridges, comprising a support for such belt, means associated with said support for feeding the belt across said support, connectible and disconnectible drive means for said feeding means, means associated with said support for extracting a cartridge from the belt, connectible and disconnectible drive means for said extracting means, means associated with said support for detecting a defect in the belt, and means connected between said detecting means and both of said drive means and operable in response to the detection of a defect in the belt for disconnecting the drive means for the feeding means and for connecting the drive means for the extracting means.

7. Apparatus for the detection of defects in an ammunition belt of the flexible type containing a series of removable cartridges, comprising a support for such belt, means associated with said support for feeding the belt across said support, connectible and disconnectible drive means for said feeding means, means associated with said support for extracting a cartridge from the belt, connectible and disconnectible drive means for said extracting means, means associated with said support for detecting a defect in the belt, means connected between said detecting means and both of said drive means and operable in response to the detection of a defect in the belt for disconnecting the drive means for the feeding means and for connecting the drive means for the extracting means, and means connected between said drive means and operable in response to predetermined operation of said extracting means to disconnect said drive means for said extracting means and to connect said drive means for said feeding means.

8. Apparatus for the detection of defective components in an ammunition belt of the type consisting of a series of like belt links articulatedly interconnected by cartridges, comprising a support for such belt, means for feeding the belt across said support, gage means associated with said support and arranged to detect defects in components of the belt, means for extracting a pair of cartridges from a component determined by said gage means to be defective, connectible and disconnectible drive means for said extracting means, and means responsive to the detection of a defective component by said gage means to connect said drive means for the extracting means for the extraction of a pair of cartridges from the defective link.

9. Apparatus for the detection of defective components in an ammunition belt of the type consisting of a series of like belt links articulatedly interconnected by cartridges, comprising a support for such belt, means for feeding the belt across said support, gage means associated with said support and arranged to detect defects in components of the belt, means for extracting a cartridge from a component determined by said gage means to be defective, connectible and disconnectible drive means for said extracting means, and means responsive to the detection of a defective component by said gage means to con-

nect said drive means for the extracting means for the extraction of a cartridge from the defective link.

10. In an apparatus including gage means for the detection of defects in a cartridge belt or the like, means for extracting cartridges upon the detection of a defect and driving means for the extracting means; electrical control means for the driving means comprising, in combination with the gage means, a source of electrical energy, first switch means connected to said source of energy and arranged for actuation by said gage means upon the detection of a defect in the belt, a solenoid connected to said first switch means and energizable thereby upon operation of the gage means, second switch means connected to said source of energy and arranged for actuation to effect operation of the drive means for the extracting means, retractable means operable in response to energizing of said solenoid by said first switch means to close said second switch means, means connected to said retractable means and operable in response to initial energizing of said solenoid to maintain closed position of said second switch means even though said solenoid is de-energized, and means operable in response to completion of cartridge extraction for retracting said retractable means to open said second switch means.
11. In an apparatus including gage means for the detection of defects in a cartridge belt or the like, means for extracting cartridges upon the detection of a defect and driving means for the extracting means, electrical control means for the driving means comprising, in combination with the gage means, a source of electrical energy, first switch means connected to said source of energy and arranged for actuation by said gage means upon the detection of a defect in the belt, a solenoid connected to said first switch means and energizable thereby upon operation of the gage means, second switch means connected to said source of energy and arranged for actuation to effect operation of the drive means for the extracting means, retractable means including a normally cocked latch operable in response to energizing of said solenoid by said first switch means to close said second switch means, means connected to said retractable means and operable in response to initial energizing of said solenoid for releasing said cocked latch to maintain closed position of said second switch means even though said solenoid is de-energized, and means operable in response to completion of cartridge extraction for retracting said retractable means and re-cocking said latch to open said second switch means.
12. Apparatus for detecting defects in an ammunition belt of the type containing a series of axially removable cartridges, comprising a support for carrying such belt with the axes of the cartridges lying generally in a horizontal plane, gage means associated with said support and arranged in gaging relation to the belt to detect defects therein, feeding means for moving the belt past said gage means, means connected between said gage means and feeding means and operable in response to detection of a defect in the belt to interrupt operation of said feeding means, means operable to extract a cartridge generally horizontally axially from the portion of the belt determined to be defective and means operating said extracting means only in response to detection of a defect in said belt by said gage means.

13. An apparatus as claimed in claim 12, in which said extracting means includes a supporting element for supporting the cartridge to be extracted generally in its horizontal position during the extracting operation.

14. An apparatus as claimed in claim 12, in which said extracting means comprises a plurality of gripping elements for gripping the extracting groove of the cartridge to be extracted, one of said elements having a supporting portion for supporting the cartridge generally in its horizontal position during the extracting operation.

15. An apparatus as claimed in claim 12, in which said extracting means includes means for releasably gripping the cartridge to be extracted, a generally hollow member into which the extracted cartridge may be withdrawn by said gripping means, means for supporting the cartridge generally in its horizontal position during extraction thereof and while the cartridge is being withdrawn into said hollow member, means for releasing said gripping means when the cartridge is within said hollow member, and means forming an elongated generally horizontal opening in said hollow member through which the extracted and released cartridge may pass.

16. Apparatus for detecting defects in an ammunition belt of the type containing a series of axially removable cartridges, comprising a support for carrying such belt with the axes of the cartridges lying generally in a horizontal plane, gage means associated with said support and arranged in gaging relation to the belt to detect defects therein, feeding means for moving the belt past said gage means, and operable in response to detection of a defect in the belt to interrupt operation of said feeding means, means for releasably gripping a cartridge and extracting the same from the belt portion determined to be defective, means operable in response to detection of a defect in said belt by said gage means to interrupt operation of said feeding means and effect operation of said extracting means to extract a cartridge at the defective portion of said belt means for supporting the extracted cartridge generally in its horizontal position during the extracting operation, and means operable upon completion of the extracting operation for releasing said gripping means for freeing the cartridge therefrom.

17. Apparatus for detecting defects in a flexible ammunition belt containing a plurality of axially removable cartridges, comprising a support for carrying such belt, gage means associated with said support and arranged in gaging relation to the belt to detect defects therein, feeding means for moving the belt past said gage means, means for extracting a cartridge axially from the belt portion determined to be defective and means operable in response to detection of a defect in said belt to interrupt operation of said feeding means and simultaneously to extract a cartridge axially from said belt at the defective portion thereof.

18. Apparatus as claimed in claim 17, in which said extracting means includes a supporting element for supporting the cartridge to be extracted generally in its original horizontal position during the extracting operation.

19. Apparatus as claimed in claim 17, in which said extracting means comprises a plurality of gripping elements for gripping the extracting groove of each cartridge to be extracted, one of said elements having a supporting portion for

translating the cartridge axially during the extracting operation.

20. An apparatus as claimed in claim 17, in which said extracting means includes means for releasably gripping each cartridge to be extracted, a generally hollow member into which the extracted cartridges may be withdrawn by said gripping means, means for translating the cartridge axially during extraction thereof toward said hollow member, and means for releasing said gripping means when the cartridge is within said hollow member, there being an elongated opening in said hollow member so disposed and shaped that the extracted and released cartridges may pass therethrough.

21. Apparatus for detecting defects in an ammunition belt of the type containing a plurality of axially removable cartridges, comprising a support for carrying such belt with the axes of the cartridges lying generally in a horizontal plane, gage means associated with said support and arranged in gaging relation to the belt to detect defects therein, feeding means for moving the belt past said gage means, and operable in response to detection of a defect in the belt to interrupt operation of said feeding means, means for releasably gripping a cartridge and extracting the same from the belt portion determined by said gage means to be defective, means operable in response to detection of a defect in said belt to interrupt operation of said feeding means and simultaneously to effect operation of said extracting means, said extracting means translating the extracted cartridge axially, and means operable in response to completion of the extracting operation for releasing said gripping means for freeing the cartridge therefrom.

22. Apparatus for detecting defects in an ammunition belt of the type containing a plurality of axially extractible cartridges the nose and base portions of which project laterally respectively at opposite sides of the belt, comprising a support for carrying such belt for movement in a path along the main axis of the belt, means on said support including a pair of guide elements spaced laterally of the path of movement of the belt over the support, said elements being arranged respectively to engage nose and base portions of cartridges in the belt, gage means arranged on the support intermediate said guide elements and having a gage portion spaced laterally a predetermined distance from one of said elements and disposed to engage side portions of the belt and may be laterally displaced and therefore non-coincident with said distance, and means connected to said gage means to indicate lateral displacement of belt portions with respect to nose and base portions of the cartridges.

23. Apparatus for detecting defects in an ammunition belt of the type containing a plurality of axially extractible cartridges the nose and base portions of which project laterally respectively at opposite sides of the belt, comprising a support for carrying such belt for movement in a path along the main axis of the belt, means on said support including a pair of guide elements spaced laterally of the path of movement of the belt over the support, said elements being arranged respectively to engage nose and base portions of cartridges in the belt, gage means arranged on the support intermediate said guide elements and having a gage portion spaced laterally a predetermined distance from one of said

elements and disposed to engage side portions of the belt that may be laterally displaced and therefore non-coincident with said distance, means on said support for extracting a pair of cartridges from a belt portion passing the gage means, and means connected between said extracting means and said gage means and operable in response to detection by said gage means of lateral displacement of a belt portion with respect to nose and base portions of a pair of cartridges for actuating said extracting means for the extraction of said pair of cartridges.

24. In an apparatus for the detection of defective links in an ammunition belt of the type wherein a series of like belt links are articulately interconnected by cartridges, comprising, means for supporting an ammunition belt, gaging means associated with said supporting means, means operable to advance said belt on said supporting means in step-by-step movement past and in operative relation with said gaging means, means operable to extract the pair of cartridges pivoted in the link in gaging relation with said gaging means, power means, drive means operable alternatively to connect said power means to said belt advancing means

25

or to said cartridge extracting means and normally connected to drive said advancing means, and means responsive to detection of a defective link by said gaging means to disconnect said drive means from said advancing means and to simultaneously connect the same to said extracting means.

STEPHEN C. OLSZEWSKI.
